UNITED STATES PATENT OFFICE.

GEORGE A. BURNHAM, OF SAUGUS, MASSACHUSETTS, ASSIGNOR TO SEARS B. CONDIT, OF BROOKLINE, MASSACHUSETTS.

ELECTRIC SWITCH.

Application filed April 28, 1922. Serial No. 557,058.

To all whom it may concern:

Be it known that I, GEORGE A. BURNHAM, a citizen of the United States, residing at Saugus, in the county of Essex and State of Massachusetts, have invented an Improvement in Electric Switches, of which the following is a specification.

This invention relates to oil immersed electric switches especially adapted to control direct current circuits.

Oil immersed electric switches are universally used to control alternating current circuits and the circuit is interrupted under oil or other equivalent fluid.

A direct current circuit cannot ordinarily be interrupted in oil for the reason that the arc will usually persist, regardless of the separation of the arcing members, and generate such a volume of gas and vapor as to cause damage to the switch. Consequently, it has been universal practice to control direct current circuits by air-break switches and interrupt the circuit in air.

For large volumes of direct current, the air-break switch includes a main current-carrying member comprising a brush member built up of a plurality of laminæ, and current interrupting members comprising auxiliary contact or arcing members from which the arc is drawn and by which the direct current circuit is interrupted.

For high values of direct current, the brush member, while relatively massive, becomes heated, and the contact junctions between the brush member and the stationary switch studs or contact blocks, especially, become heated and oxidize; and the contact resistance at these points becomes increased, and increased heating results.

By reason of the oxidization of the contact surface, constant inspection and cleaning of the switch is necessary to maintain the switch in good working order.

An object of this invention is to provide a switch for direct current circuits wherein the main current carrying components are shielded or insulated from the oxidizing influence of the atmosphere.

In carrying out the invention, I prefer to immerse the main current carrying members in a non-oxidizing and preferably electrically-insulating fluid by which said members are insulated and shielded from the oxidizing influence of the atmosphere. The main cur-

rent-carrying members are not adapted to 55 interrupt the direct current circuit, and I provide auxiliary contact or arcing members without the insulating fluid and disposed in and surrounded by the air to strike the arc and interrupt the direct current circuit. With this arrangement, the direct current is carried under an insulating fluid and interrupted in air.

The figure represents diagrammatically a direct current electric switch embodying the 65 invention.

As here shown, the direct current switch includes the switch frame 10 comprising a cover for the receptacle 11 which is adapted to contain some insulating fluid, as oil, in 70 which the main current carrying members of the switch are immersed and insulated from the oxidizing influence of the atmosphere. The main stationary switch members 12 and 13 are carried by the switch 75 frame 10 and terminate in contact blocks 14 and 15 which are immersed beneath the fluid in the receptacle. The main movable switch or bridging member comprises the brush member 16 which is carried on the end of 80 the switch rod 17 and immersed in the fluid in the receptacle. The brush member is adapted to contact with and bridge the contact blocks 14 and 15 and conduct direct current therebetween but it is not adapted to 85 interrupt the direct current circuit. The circuit is adapted to be interrupted in the air and for this purpose, the stationary auxiliary switch contact or arcing members 18 and 19 are disposed above the receptacle and 90 exposed to and surrounded by air and suitably supported in position. Said arcing members 18 and 19 are connected with the main switch members 12 and 13 by the conductors 20 and 21 respectively. An auxiliary bridging member 22 may be carried by the switch rod 17 or otherwise arranged to be movable into and away from bridging relation with the arcing members 18 and 19. Said auxiliary bridging member 22 and arcing members 18 and 19 are not adapted normally to carry any appreciable current; and the main switch members 12 and 13 and main brush member 16 are adapted normally to carry substantially the entire direct 100 current load.

The arcing members 18 and 19 and auxiliary bridging member 22, and main switch

members 12 and 13 and main brush member 16, are so arranged that, in normal switch-closed position, the direct current is carried by the main brush member. When the switch is moved toward open position, said brush member breaks contact with the contact blocks 14 and 15 of the main switch members but, as the auxiliary bridging member 22 is yet in contact with the arcing members 18 and 19, the current is transferred to and carried by said arcing members and no interruption of the direct current circuit, or arcing, takes place under the insulating fluid. A further movement of the switch rod 17 towards switch-open position effects the final interruption of the direct current circuit at the arcing members 18 and 19 and the circuit-interrupting arc is drawn in air at the arcing members.

20 In closing the switch, the circuit is first completed in air through the arcing members 18 and 19 and subsequently carried in the insulating fluid through the main brush member 16.

25 With this arrangement, it will be noted that the main current carrying components are immersed in an insulating fluid and thereby protected from the oxidizing effect of the air, and the current is carried in the insulating fluid and interrupted in air.

I claim:

1. A direct current electric switch having main current carrying components immersed in an insulating fluid, and arcing members disposed in and surrounded by air.

2. A direct current electric switch having main contact members, and a main bridging member immersed in an insulating fluid, and arcing members disposed in and surrounded by air.

40 3. A direct current electric switch having main circuit-control members immersed in an insulating fluid, and auxiliary circuit-control members arranged in shunt with said

main circuit-control members and disposed 45 in and surrounded by air.

4. A direct current electric switch having a receptacle adapted to contain an insulating fluid, main contact and bridging members immersed in the fluid in said receptacle, 50 and auxiliary contact members arranged in shunt with said main contact and bridging members and disposed in and surrounded by air.

5. A direct current electric switch having 55 means disposed in an insulating medium to carry the current in shunt with the aforesaid means to interrupt the circuit in air.

6. An electric switch having a receptacle adapted to contain an insulating fluid, main 60 contact and bridging members immersed in the fluid in said receptacle, arcing members disposed in and surrounded by air and connected electrically with said main contact members, and means to interrupt the circuit through the switch at said arcing members.

7. Direct current switch apparatus comprising an oil immersed switch and an air-break switch electrically connected in parallel, and operating means for said switches arranged to open the air break switch last.

8. Direct current switching apparatus comprising an oil immersed switch and an air-break switch electrically connected in 75 parallel, and operating means for said switches arranged to open the air break switch last and close it first.

9. Electrical switching apparatus comprising two switches electrically connected 80 in parallel, one of said switches surrounded by air and said other switch shielded from the air, and operating means for said switches arranged to open the shielded switch first.

In testimony whereof, I have signed my name to this specification.

GEORGE A. BURNHAM.
